(57) CLAIM

The ornamental design for a canister housing, as shown.

DESCRIPTION

FIG. 1 is a perspective view of a canister housing, showing my design with a removable cover secured thereto;

FIG. 2 is a right side view of the canister housing of FIG. 1 with the cover removed;

FIG. 3 is a left side view of the canister housing of FIG. 1 with the cover removed;

FIG. 4 is a top view of the canister housing of FIG. 1;

FIG. 5 is a bottom view of the canister housing of FIG. 1;

FIG. 6 is a front view of the canister housing of FIG. 1 with the cover removed; and,

FIG. 7 is a back view of the canister housing of FIG. 1 with the cover removed.

The dashed lines indicating threads are not part of the design and are included for illustrating the use of the invention.
